Application August 19, 1932, Serial No. 629,526

16 Claims. (Cl. 84—1)

This invention relates more particularly to a method of and means for producing and augmenting the effect of electrical pulsations used in certain types of electrical musical instruments in which sonorous bodies or resonant masses are actuated by electromagnets energized by a current of electricity rendered periodically intermittent, undulatory or pulsatory.

An important object of the invention is the attainment and maintenance of a scale having a high degree of perfection, whether the instrument is frequently used or is left idle for long periods.

Another important object of the invention is the attainment of an improved quality of tone and a vastly greater efficiency without any increase of the voltage or amperage of the intermittent, undulatory or pulsatory current and, consequently, with a much increased life, volume 20 for volume of the tone, of the interrupting mechanism.

A further object of the invention is materially to lessen the cost of operating the instrument, very little current, relatively, being necessary for 25 a large volume of tone.

A further object of the invention is the attainment of much greater simplicity and cheapness of construction, very little additional wiring being necessary in the preferred form here disclosed.

Still another important object is the attainment of a quicker, crisper, and more staccato attack of the tones, making possible the most rapid and delicate types of music with a technique as 35 versatile and rapid at least, as that of the violin in the hands of a maestro.

Another and most important object of the invention is the efficient and cheap operation of sounders used in electrical musical instruments 40 producing tones synthetically after the general method set forth in a patent granted to me October 29, 1929 and Numbered 1,733,630, so as to permit the several component parts of the various complex tones built up to be easily and simply 45 synthesized.

A further object of the invention is a still greater increase of efficiency through the employment of sounders having a magnetic circuit with but one air-gap in each case.

Other features of the invention pertain to the order, construction, and grouping of parts so as to permit the attainment of any desired timbres, as for example, by the means set forth in the 55 patent just referred to, and the proper grading

of musical utterances for purposes of artistic expression.

In U. S. Patent No. 814,878 issued to M. L. Severy and G. B. Sinclair, and dated March 13, 1906, the sonorous bodies were actuated by electromagnets the energizing current of which was pulsated by being passed through revolving commutating mechanism traversing brushes. As a result of this arrangement, the sounding of each tone produced at its associated brush a number 60 of arcs per second equal to the number of vibrations necessary to educe such tone, and as the current used was relatively large for loud tones, the arcs were very destructive of the commutators. These soon roughened and the brushes had 65 often to be changed. Nor was this all, for as soon as the commutators became uneven the tone suffered, due to imperfect contact and imperfect timing thereof. Various attempts were made to remedy these difficulties, but no way was 70 found to prevent the rapid deterioration of the devices.

In my co-pending application, Serial No. 455,- 876, filed May 26, 1930, I describe a method of pulsating an electrical current in a manner to 80 render negligible any arcing at the commutator. This is accomplished by having the magnetism rising in the associated core at the time that its brush breaks at the commutator. Two currents are used, one which is steady in the coil, and another which is interrupted at the commutator. The action of one of the currents thus tends to neutralize the other, so that when both currents are on together the core is at its minimum of magnetism; or preferably, as ordinarily used, 85 without magnetism at all. In this present case a current passing through the commutating mechanism, and another passing around the same is also used, but the principle of this use is entirely distinct and for the most part diametrically opposite. Here the polarities are alike and the current, which is steady about a speaking-magnet core during the pressure of its associated key, does not periodically decrease and augment the effect of the current passing through the 90 commutator, but greatly augments the effect of the commutator current at all times during the speech of the associated magnet and sounder. In this case there is no reversal of polarity, and the commutator current has its effect greatly 95 enhanced by reason of the fact that its relatively weak pulsations are made to act in a comparatively strong magnetic field already prepared for them. When the current is turned on by the pressure of the key, the steady current starts the 100 105 110

vibration instantly whether or not the brush is on a conducting section, the response being both stronger and quicker, while the tone is also clearer and cleaner.

5 In the forms of this present case where two coils are used, it is to be noted that the coils are not wound one over the other, or even with two parallel wires wound about the core in one operation, as this has been found unsatisfactory; 10 neither are they wound to produce opposite polarity. Where two coils are used I prefer to wind them separately, each coil occupying its own separate position on the core, and to connect them with entirely independent circuits as shown, the 15 current passing through one coil not passing through the other.

Condensers, which may vary in capacity with the periodicity of the interruption, may be used across the break and across the magnet as well 20 and, especially with the lower frequencies of interruption, these condensers will commonly be used simultaneously, thereby suppressing practically all of the arc.

In the drawings: 25 Fig. 1 is a diagrammatic lay-out of the preferred form of my invention;

Fig. 2 is a diagrammatic lay-out of another form of my invention using two coils with each speaking magnet;

30 Fig. 3 is a similar view of a further form of my invention in which permanently magnetized cores are used, embodying also means for renewing the magnetism of said cores at necessary intervals;

Fig. 18 is a side elevation of a sounder particularly adapted to the low bass notes of the instrument;

55 Fig. 19 is a detail view of a damping mechanism for the sounders for the low bass notes of the instrument.

Referring to Fig. 1, the numeral 5 indicates a 60 source of direct current. A wire 6 leading therefrom connects with wire 7 which leads to brush 8 supplying commutators 9 through shaft 10, with positive current. The commutators 9 are understood to be revolving at correctly timed speeds, 65 and upon them rest brushes 11. The commutators are provided with varying numbers of teeth between which are spaces filled with a material of high resistance or with an electrical insulation, so that, as the commutators revolve, a pulsating 70 current is delivered through the brushes 11 and wires 12 to the coils 13 wound upon soft iron cores 14, of the speaking magnets. The other terminal of each of these coils 13 is wired to a second contact 15 of a relay shown here as directly above 75 the speaking magnets. It will be noted that each

of these relays is provided with ten pairs of co-acting contacts, and some of these contacts are, as shown, connected with portions of the partial-mixing system seen above them. As the purpose of this wiring is fully set forth in my copending application, Serial No. 472,969, filed August 4, 1930, (now Patent No. 1,899,884 dated February 28, 1933, and as it is necessary to show it here only to indicate one feature of the present invention, it will be described only as it applies to this present application.

Tracing the circuit energizing the coils 13 it will be seen that positive current flows via wire 6 to the wire 7 thence to brush 8, shaft 10, commutators 9, brushes 11 and wires 12 to one pole of each magnet-coil 13, thus serving said coil with pulsating current of a periodicity determined by the associated commutator 9. The same pole of these coils 13 is also served with unpulsated current during the sounding of associated sounders, the circuit being as follows: From wire 6 by wires 16 to resistances 17 and wires 12 to the already mentioned poles of the speaking-magnets, and from the other poles of said magnets by wires 18 to the second contacts 15 of the relay system already referred to. From these contacts 15 both the pulsated and the unpulsated currents pass together through the relay system diagrammatically represented by the contacts 15, 15^a, 15^b, 15^c, and so on; through the partial-mixing system 105 diagrammatically represented by the switches 4, 4^a, 4^b, 4^c, 4^d, etc., by means of the wires 3; through the expression-control system represented diagrammatically by the switches 2, 2^a, 2^b, 2^c, etc., by means of the wires 1; and by the 110 wire 86 to the tremolo mechanism diagrammatically represented at 87, said currents returning to the negative side of generator 5 by means of the wire 88.

In some applications of my invention it is unnecessary to pass both the pulsatory and the unpulsated currents together through the different mechanisms, since the two currents may be kept essentially independent of each other. In the embodiment shown in Fig. 1, however, the tone 115 qualities are synthetically built up, and it is desirable that the pressure of a single key of the manual shall often cause a plurality of sounders to speak, one for each partial of the timbre desired. It will therefore be obvious that, since a 120 given key is normally associated with a given relay which it operates, this relay must be able to elicit all the tones necessary for the partials required for the predetermined tone quality.

This is made plain in Fig. 1, where the pair 120 of contacts 15 of the left-hand relay represent the prime or first partial of the tone associated with that relay, this tone being normally excited by the pressure of the first note of the key-manual, which in the case of my instruments is the 125 note C of 32.33 vibrations per second. The next co-acting pair of contacts, 15^a, above that already mentioned is associated with the second partial of this note C of 32.33 vibrations, and the pair 15^b above that with the third partial of 140 the same note, and so on in order for the rest of the partials available. The lower pair of contacts of each relay is used for a graded sub-octave and, as the note #1 here indicated has no such sub-octave, it cannot be wired to anything 145 below. It will be noted that the right-hand contact of each pair in the relay associated with note #1 is wired to the similar contact of the relay associated with note #2, as set forth in my aforesaid companion application, Serial No. 472,969. 150

results. Where current consumption is of no moment, even more could doubtless be used, the limit being that point so near saturation that the relatively weak pulsating current is unable to produce a sufficient change in the magnetic flux to attain good results.

Fig. 2 differs from Fig. 1 principally in that a second coil 24 is carried by each of the speaking magnets, the function of which is steadily to magnetize the core 14 during the pressure of its associated key, through the agency of current which does not pass the commutator brushes 11. Condensers 25 across the poles of these coils 24 serve to absorb the arc when the current is cut out of them upon the release of their associated keys. The form shown in Fig. 2 is slightly more efficient for the same amount of current than the simpler embodiment shown in Fig. 1 by reason of the fact that the resistance 17, Fig. 1, merely holds down the current without being in itself productive of any magnetization of the core 14, while the coils 24 hold down the current by resistance which is productive of magnetism. In actual practice it has been found that it takes about one-fifth more current to produce the same volume of tone, other things being equal, where the resistances 17 are used instead of the coils 24. Over against this is the increased cost of the coils, and as the current consumption is very small anyway, the arrangement set forth in Fig. 1 is preferred for all ordinary purposes.

It is to be understood that the operative system or circuit, so-called, is not shown in these figures as it would needlessly complicate the drawings. It will suffice if it be simply understood that when a key of the manual is played an associated magnet is actuated, with the result that the ten pairs of co-acting contacts such as 15, 15^a, 15^b, 15^c, etc. of its associated relay, are brought into touch, thus providing a path or paths through the rest of the system by which the current returns to the other side of said source 5.

In the partial switches diagrammatically shown in Figs. 1 and 2 it will be noted that the resistances 4' are omitted from all the switches 4, since said switches 4 are merely used as cut-out switches to prevent partials sounding at all when they are not wanted in tonal combinations. These 50 partial switches and the switches 2, 2^a, etc. of the expression-control system above them are diagrammatic representations, in part, of what I term my "permuting system", which is clearly set forth in my application Serial No. 650,179, filed 55 January 4, 1933.

In Fig. 3 a variant form of the construction of Fig. 1 is shown, which may be used in certain types of instruments not requiring the maximum power possible to attain, or the greatest 60 possible evenness of scale. In this case the core 14' is a permanently magnetized core of steel carrying a coil 13', the connections to the commutating mechanism being, in principle, similar to those of Figs. 1 and 2. The magnetism 65 of the cores 14', whether it be produced as in Figs. 1 or 2, or by the so-called permanent magnetism of Fig. 3, has a very great effect upon the volume of tone, and this effect, of course, other things being equal and up to that 70 certain point of saturation already adverted to, will vary as the magnetism produced by either of the two last-named agencies varies. This variation, however, will not be in simple proportion, for the pull between a magnet and its 75 armature is proportional to the square of the

number of magnetic lines that come into action. It is by taking advantage of this geometrical proportion that I secure the remarkable results made possible by this invention. It must, however, be borne in mind that just because of this remarkable increase in efficiency it is all the more impossible to obtain an even scale in an instrument using any form of my present invention, if its unpulsating magnetic factor, whether produced by electromagnetism or permanent magnetism, be not thoroughly dependable as to strength, both as between different parts of the scale at one time or at different times, and as between the whole scale at different times. Not only must the scale be even in its parts, but the augmenting magnetic factor, of either type, must not be strong today and weak a month or three months hence, not even if every tone-augmenting magnetic factor in the instrument vary in like proportion, for, as will readily be seen, the resistances used in the partial-mixing and expression-control systems are definitely wired into the instrument, and cannot be adjusted at will to compensate for fortuitous variations of volume.

It is of course well known that permanent magnets lose a portion of their magnetism after magnetization, and where they are not provided with a keeper securing a magnetically closed circuit, they will lose their power relatively fast. 105 Many other factors likewise enter into this loss of power, one of the most important being vibration, jar or impact, so that permanent magnets in a situation where there is great and constant vibration during use, as in the case of 110 a powerful musical instrument, cannot be depended upon to keep their original magnetism sufficiently well to suffice for any but the cheaper and less exacting types of instruments. It is for this reason that it is preferred, where permanently magnetized cores are used and the cost is not prohibitive for the type of instrument, to provide a means for quickly raising and evening up the magnetic intensities of these permanently magnetized cores. A convenient way of doing 115 this manually is shown in Fig. 3, but it is to be understood that it may be done automatically at fixed intervals, as for example, each time an instrument is turned on, a strong current may be momentarily let into all the coils 13' surrounding the permanently magnetized cores 14'. This method is, of course, within the scope of my invention as well as the method of accomplishing the same result manually which is here shown.

It is to be remembered that it is always desirable 130 to pass as little current as possible through the commutators, for reasons which will be apparent, and it is the very purpose of this invention to decrease immensely the amount of current which has to be handled by commutators and 135 brushes in the production of a satisfying degree of volume, so that, while the tendency of the interrupted current would be to magnetize slightly the cores of hard steel around which it passes, it is far too weak to be of any great assistance 140 in keeping the cores up to strength after they are once magnetized. Since some sections of the instrument are inevitably played far more than other sections, it is imperative that the magnetism of the cores shall be sufficiently strong 145 not to be increased by the passage of this weak pulsating current, lest it should be impossible to maintain an evenness of scale.

It is for these reasons that I provide the remagnetizing mechanism shown in Fig. 3, where 150

It will now be seen, in view of what has just been said, that it is necessary in this preferred form of synthetic tone production shown at Fig. 1 to pass both the pulsated and the unpulsated currents through the relay system, the partial-mixing system, the expression-control system, and the tremolo system, despite the fact that this additional current will require all resistances throughout the various systems to be of some what larger capacity. Tracing the circuit with respect to a fundamental and a single higher partial will make this plain. Suppose the key associated with note #1 of the manual be pressed and the quality desired is such that a third partial is used. Under these circumstances a third-partial switch will be closed as well as the fundamental or first-partial switch, and this will supply negative current to right-hand contacts 15, 15^b of the relay system, so that as soon as the playing of the proper key closes the co-acting contacts of the associated relay, this negative current crosses to the left-hand contact 15 and by wire 18 to coil 13 of the associated speaking-magnet, and thence from the other terminal of said coil 13 by wire 12, brush 11 and commutator 9 back to generator 5 by wire 6, thus completing the pulsating circuit. Current also passes from the right-hand pole of the associated speaking-magnet by wire 12 to resistance 17 and wire 16 back to generator 5 by wire 6, thus completing the unpulsated circuit, it being noted that this unpulsated current passes around and not through the commutator. While this is occurring, current is crossing from the right-hand to the left-hand contact 15^b, whence it passes by wire 19 to the left-hand contact 15 of the second pair of co-acting contacts of the relay normally associated with note #20, which note is a musical twelfth above note #1 and is, therefore, in the relation of a third partial thereto. From this last-mentioned left-hand contact 15 current passes, without the closing of the associated relay, to coil 13 of the speaking magnet associated with note #20; thence through commutator 9 in one case, and around it and through the resistance 17 in the other, passing back through wire 6 to the positive pole of generator 5.

Condensers, which will vary greatly in capacity according to the frequency of the pulsations of the commutators 9, are distributed to attain the best results possible. For some pitches, a condenser 20 connected to brush 11 on one side and by the wire 21 to the wire 6 on the other side, is placed across the break, while in other cases it is found to work quite as well placed across the coil as shown at 22, a wire 23 connecting the condenser with wire 12 and thereby with the other connections leading to the speaking-magnet, the wire 24 joining said condenser to the other pole of said magnet. In some cases I find that condensers placed in both of these positions give the best results of all by suppressing practically all the arc. In Fig. 1 it will be noted that the resistances 17 are in shunt with the condensers 20.

The placement of the resistances 17 is illustrated in detail in Figs. 8, 9 and 10, but in each instance the co-acting contacts 80, 81 are operated directly by pressure of the keys of the manual, and not through the relay system of Figs. 1 and 2. Condensers have been omitted in Figs. 9 and 10, but may be used as described in connection with any of the other figures, for the purpose of decreasing the arcing at the commutators. The resistances 17 may be replaced by, or used in conjunction with a resistance placed

in the brush member itself as shown in Fig. 14, and as will be more fully described later. A resistance so placed and of contacting dimensions sufficient to bridge the gaps between teeth of the commutator, will give a continuous current after the manner of the resistance 17, but it is to be noted that in such practice all the current which passes the high resistance member, as well as the pulsated current which traverses the low resistance part of the brush, passes through the commutator. Furthermore, should the brush contact vary in the rotation of the commutator, this high resistance member would be materially affected thereby, whereas the resistance 17 would not. Balanced against these considerations, however, are the facts that the brushes carrying the relatively thick, high resistances prevent the tendency of the metallic part of the brush to "dig" into and so wear the commutator. Moreover, the high resistance member may be provided with a lubricant, as graphite, which will still further assist in the protection of the commutator. Indeed, so important are these last-named factors that even where the resistance member 17 is used, it may be desirable to use also the broadened brush member or members with or without the lubricating factor, even when their resistance is so high as to be sensibly infinite and their passage of current negligible.

The placing of very high resistances in parallel with condensers is well known and is said to have originated with von Helmholtz, who used it solely for the purpose of aiding in the suppression of arcing. While I have tried this method many times, it has not produced any outstanding diminution of arc, although it apparently did change the color of the arc and so, perhaps, lower its burning proclivities. Very high resistances were employed according to well-known practice, and these were usually made non-inductive. It has also been proposed to use very high resistances which must always be non-inductive, that is, not coiled, placed across that part of the circuit where the gap is to be made at break, so that the arc will not so readily leap the air-gap but will pass through this high non-inductive resistance. It has been stated that a coiled wire is of no use, as the discharge refuses to go around its convolutions, and a very thin platinum wire has been suggested, or even a streak of a plumbago pencil on a roughened surface. The resistance to be used should, according to various formulas proposed, be from forty to sixty times that of the magnet coil. Shunting with a condenser either across the break or across the coil is common, though I am not aware that condensers have heretofore been used in both places at once. The point to be borne in mind in this present case is that this application is not directed to suppression of the arc, but to increase of the magnetic efficiency without altering the arc in any sensible way. Therefore, the resistance 17 of Fig. 1 need not necessarily be non-inductive whether it be placed across the break as in said figure, or across the magnet coil as in Fig. 10, for in this invention its use is a steady one throughout each pressure of the associated key. In this present invention the value of the resistance 17 is so lowered that it provides a strong, steady magnetic field in which the pulsating current passing the commutator acts, thereby greatly enhancing and improving the tone. I find in the preferred form with a current of thirty volts, that a steady flow of from a fifth to a quarter of an ampere about the coils 13 gives most excellent

a manual or automatic stop 26, or similar means, is shown for closing a switch against the action of a spring 27, and causing a bar 28 to bridge co-acting contacts 29, 29', thus energizing magnets 30, 31 and 32, the path of the current being as follows: From the plus pole of the generator 5 by wire 33 to contact member 29; thence by the bridging bar 28 to contact member 29'; thence by wires 34 and 35 to wire 36; thence to one pole of each of the magnets 30, 31 and from the other poles of each of said magnets by wire 37 to wire 38; and thence by wire 6 back to the minus pole of generator 5, thus energizing magnets 30, 31. The wire 34 also runs to one pole of magnet 32, the other pole of said magnet being joined, through a wire 6, with the minus side of generator 5, thus energizing magnet 32 so that, when stop 26 is pressed to the right, magnets 30, 31 and 32 are all energized. The functions performed by the magnets 30, 31 and 32, when energized, are as follows:

The magnets 30 and 31 attract and pull down arms 39 to which are attached bridging bars 40, 40' adapted to contact co-acting members 41, 41', 42 and 43, members 42 and 43 each being in number equal to all the speaking-magnets of the instrument whose cores are to be magnetized by this device. The bridging bars 40, 40' are broken away to indicate that they bridge many more contacts than are shown, only the principle of operation being here indicated. It will be noted that wires 44 join one pole of all the speaking-magnets to contacts 42 bridged by bar 40, while all the other poles of said speaking-magnets are joined by wires 45 through resistances 46 to contacts 43 coating with the bridging bar 40'. The contact 41' is joined to a contact member 48 which co-acts with a member 49 in circuit with a wire 6 leading to the negative pole of the generator. When magnets 30, 31 and 32 are energized, armature 50 is drawn upwardly against the action of spring 51, thereby closing contact 49 against contact 48 and separating contact 49 from contact 52, thus cutting off the negative pole of the generator from wire 7, brush 8 and commutator shaft 10. At the same time the circuits in all the coils 13' of the speaking-magnets are completed without any passage of the current through the commutating mechanism, and with the full voltage of the unpulsated generator current resisted only by the resistances 46 and the resistances of the coils 13' wired in multiple, so that, with a generated current of thirty volts, with resistances 46 at fifty ohms each and coils 13' at ten ohms each, each coil 13' would be traversed by a half ampere of current during the pressure of stop 26. Immediately upon the release of stop 26, however, magnets 30, 31 and 32 are all de-energized, member 49 contacts with member 52, leaving member 48; bridging bars 40, 40' move upwardly; and the whole system is ready for tone production by the energization of the speaking-magnets by the pulsated current from the commutators 9 assisted by the magnetization in the cores 14'.

The system shown in Fig. 3 is not without some advantages over that shown in Fig. 2 as, for example, dispensing with one coil on each speaking-magnet core, but this is more than overbalanced by the fact that the results are much inferior with permanent than with electromagnetic magnetization, for it is not feasible to magnetize permanently to the same degree of strength that can be attained by the electro-

magnetic method, to say nothing of the difficulty of securing constant and constantly persisting magnetization. These reasons, without going into others, are sufficient to explain why I prefer, whenever possible, to use the construction shown in Fig. 1. In cheap instruments where the remagnetizing wiring may be omitted and the resulting unevenness of scale tolerated, the method of using permanent cores becomes somewhat more attractive from the cost aspect of the matter.

Fig. 4 shows two of a set of speaking units of fairly high pitch, illustrating my method of securing a magnetic circuit with only one very small air-gap. In this figure reeds 53 which may be round if desired, and are so shown, are fastened to a substantial iron casting 54, the outer ends of said reeds coming over and very near to the heads of magnet cores 14 which are adjusted up or down, for voicing, by nuts 55 upon the threaded portion of cores 14. To the ends of reeds 53 are fastened upright pins 56, adapted to carry cup-like resonators 57, 57', preferably of very light material as, for example, pasteboard, pyralin, or the like. 57' indicates a diaphragm-like bottom secured within the tube 57, the tube 57' being shown with its bottom removed and replaced by a plunger-like member 57''. The magnetic circuit is very short and the structure very efficient. The magnetic circuit is from the head of core 14 across the slight air-gap to the reed 53 of magnetizable metal, through the upright portion of casting 54 to the base thereof, and thence by nuts 55 and the threaded portion of core 14, completing the circuit. The already familiar coils 13 and 24 and their wiring need no further explanation except to state that, under the system shown in Fig. 1, the coils 24 would be dispensed with.

Fig. 5 shows a type of sounder with a single air-gap magnetic circuit, adapted to tones of lower pitch. This sounder is preferably used in a horizontal position, but may of course be placed in any desired position. Here the resonator 58, which may be a wooden pipe of square cross section, has a plunger-like member 59 formed so as to move as a whole under the action of the bar or reed 60, to the center of which it is firmly secured by screw 61. The speaking-magnet with its double coils 13 and 24 and core 14 is adjustably held by nuts 62 within the member 63, which may be circular in plan or of any other suitable conformation, its material being of a magnetizable metal. The lower end of core 14 has only a slight air-gap between it and the center of reed 60, which acts as its armature. This reed 60 is also preferably of iron or steel, and may for convenience and compactness be bent up at an angle, as shown at 64. Springs 65 of a thin magnetizable sheet metal are secured by rivets or otherwise, to the bent reed 60 at the lower ends of its upright sections, so that a magnetic metallic circuit is here secured. The other ends of springs 65 are fastened to the member 66, which are also of magnetizable metal, and are secured to the steel or iron members 67 holding the resonator 58. The magnet core 14 is adjusted to and from the reed 60, for purposes of voicing, by lowering or raising the member 68 through the agency of screws 69 and nuts 70 co-acting therewith. The upwardly bent ends of reed 60 may be weighted or shortened if the reed be not near enough to the natural pitch of the resonator with which it co-operates. The flexible hanging of reed 60 by the springs 65 renders the reed exceedingly

resonant and efficient, while at the same time it provides a practically continuous and complete magnetic circuit, as will be seen by a glance at the drawings. The forward end of core 14 is close to reed 60, which is of magnetic metal, and this reed is secured by the springs 65 of steel or iron, to the iron or steel members 66 which carry the magnetizable screws 69 upon which is fastened the iron or steel member 68 to which is secured the member 63 of magnetizable material which leads the magnetism back to the rear end of the core 14, offering a complete metallic magnetic circuit save only for the single slight air-gap between the core-head and the adjacent reed-armature 60. In this way the efficiency of these practically closed magnetic circuits is made to increase still further the efficiency of the system herein set forth. In this case also it is to be understood that if the system of Fig. 1 be adopted, coil 24 will be dispensed with.

In Fig. 6 I show a permanently magnetized core 74 into which is fastened a soft-iron core 75 around which is placed a coil 76. This construction could be used for speaking magnets as a variant of the system shown in Fig. 3, but it would be more expensive and even less efficient, and it offers no good way of keeping the permanent magnetism up to a fairly constant and efficient strength.

It is to be borne in mind that the current I use is a uni-directional and not an alternating current, and that I prefer to have the same polarity of current in both the coils 13 and 24, where both are used, as by far the best results have been obtained in this way.

There are other ways of increasing the intensity of the field in which the speaking-magnets act without increasing the current passing through the commutators, and I hold any of these to be within the province of my invention, though I have found none of them, all things considered, to be as good as the preferred form shown in Fig. 1.

Fig. 7 illustrates a method devised some years ago to decrease the arcing at the commutators. Two of the groups of rotors or commutators 9 usually employed, are here shown, each of said groups being mounted on a shaft 10, and each commutator 9 being traversed by a brush 11 as heretofore explained, the brush 8 in contact with said shaft being also shown. Each brush 11 is connected with a non-inductive resistance 17, in this case of 200 ohms, the other ends of all said resistances being joined to a bus-wire 71 connecting all the resistances 17 together throughout the instrument. From wire 71 a wire 72 leads to a non-inductive resistance 73 of 4,000 ohms, and from thence a wire 77 leads to the negative pole of the source of current. It will be seen, therefore, that when a key is pressed and the associated brush arcs, there is a 4200 ohm non-inductive resistance across the break. This system has been used with a direct current of thirty volts, and apparently makes the arc somewhat less destructive and of somewhat different color. When the resistance 73 is omitted, the aggregate current consumption of the resistances 17 in parallel, is too large. The employment of resistances aggregating 4,200 ohms permits only one one-hundred fortieth of an ampere of current to pass, and this is still further cut down by the resistance of the speaking-magnet.

In Fig. 10 a resistance 17 is shown in a location different from that of my preferred construction. It has been observed that this resistance, if of

the same value as that used for the preferred construction of Fig. 1, will cause a noticeable increase in tone when the coil 13 is taking from a fifth to a quarter of an ampere of current, but the arc will also be increased, for all the current used is made to pass the commutator, which fact is much against the system, this invention being concerned primarily with increase of tone rather than primarily with decrease of arc.

In Figs. 11 to 14 variant forms of brushes to be used with the commutators are shown, the numeral 11 in each instance indicating a conducting strip which is commonly of metal and may well be silver, placed upon the thicker members 11^a whose function is to prevent the relatively thin metallic strips 11 having a "digging" action and thus excessively wearing the commutators. The members 11^a may be impregnated with a lubricant, as graphite, or formed with a lubricant as an ingredient, as indicated at 11^b, Fig. 14, but said members are, as shown, of so high a resistance to current that at ordinary voltages they may be practically considered as insulators. In the forms shown in Figs. 12 and 13 it will be noted that the members 11^a have a still further advantage, in that they "wipe out" or quench immediately any arc which might tend to form at the leaving edge of the brush. As seen in Fig. 14 the high resistance substance 11^b, as for example, carbon or compressed graphite, is of a thickness 105 sufficient to bridge the conducting teeth of its associated commutator ring, and has a contact resistance sufficient to give the requisite amount of steady current during the pressure of its associated key, thereby serving as a substitute for the 110 resistance 17 of my preferred form shown in Fig. 1. The portion 11^b as will be obvious, serves also as a "wiper" to extinguish the arc, if any, which might be formed at the leaving edge of the low resistance member 11 of the brush. Where 115 desirable another member 11^b may be placed below the low resistance member of the brush shown in Fig. 14, after the manner shown in Fig. 13.

In Fig. 15 is shown a commutator ring 9 traversed by a brush composed of members 11, 11^a, 120 though it is to be understood that any of the brush constructions just described could be used in place of the specific one shown. The usual circuit, omitting all the unessential parts, is shown diagrammatically. This comprises the magnet 125 coil 13 and core 14, the co-acting members 83, 84 closed by pressure of a key of the manual, the source of current 5, and the connection 6 between the same and the commutator 9. When the contacts 83, 84 are closed through pressure of the 130 associated key, the circuit is completed from the brush 11 and magnet coil 13 to the minus pole of generator 5, and from the other pole thereof to commutator 9 and the bearing portion of said brush.

In Fig. 16 a brush comprising the high resistance portion 11^a and low resistance portion 11, is shown, but said brush may, wherever desirable, be of the type of Fig. 14. In this figure it will be seen that if the thicker member 11^a of the brush have, say, a surface resistance of 150 ohms when of the type of member 11^b of Fig. 14, such is its thickness when added to that of the member 11, that it will bridge the non-conducting spaces 85 between the commutator teeth, so that during the pressure of the associated key, one-fifth ampere of steady current will be flowing through the magnet (leaving out of consideration the resistance of the coil 13) when the current is that commonly used, to wit, thirty volts.

In Fig. 17 a laminated permanent magnet 89 is shown, provided at its upper end with a soft iron core 90 about which is a helix 91, one end of which is connected to a brush 11 bearing upon 5 a commutator 9 of the type shown in Figs. 1, 2 and 3. A sound-board 92, a rib 93 thereof, and a bridge 94 to which an amplifier 95 is secured, are also illustrated in this figure, the amplifier 95 carrying an armature 96, co-acting with core 10 90. A manual key 97 for completing the circuit, and the expression-control mechanism 98, 99 and 100 are diagrammatically illustrated. When key 97 is open the core 90 is magnetized and the armature 96 attracted, the commutator 9 of course 15 being driven at correct speed. When key 97 is closed, current will traverse coil 91 at each passage of a conducting section of commutator 9 beneath brush 11, thus more or less neutralizing the effect of magnet 89 upon core 90, and through 20 it, upon armature 96, which will then move somewhat away from the pole of core 90. The degree of neutralization will depend upon the relation of contacts 98, 99, that is, upon the amount of resistance inserted in the circuit of which helix 25 91 is a part. This method may be employed with advantage in instruments not requiring the maximum power possible to attain or great evenness of scale.

In the preferred form of my invention shown 30 in Fig. 1 the resistances 17 need not necessarily be non-inductive, and especially in the case of the lower notes of an instrument should not only be wound inductively, but should have a core of soft iron. If this procedure is not followed 35 the results, especially on the notes of low periodicities, are much impaired. Where this choking effect of the iron core is omitted, the pulsating part of the current seems to put a surge into the supposedly steady current, with the result 40 that the arc at the break of the pulsating system is greatly enhanced and the speech of the sounders impaired, particularly in the low sections of the instrument. Furthermore, as seen in Fig. 18 where a large horizontal sounder of the pipe 45 type is shown, the moving parts are of considerable mass and, if these are to be started promptly and damped promptly, special means must be used. In said figure the construction of the resonator is similar to that shown in Fig. 5, 50 and the same reference numerals are used to indicate similar parts. In Fig. 18, however, the coil 17' serves to supply immediate uninterrupted current to the magnet 13 the instant the corresponding key of the manual is pressed, said coil 55 serving, just as does the resistance 17 of Fig. 1, to start the tone promptly. As the coil 17' is shown with its core 101 not only serving to provide the choking action already adverted to, but also to attract rocker arm 102 and thus remove damper 103 from the vibrating member 60, 60 it will be seen that it also gives an immediate damping of the tone and cuts out all undesirable "hold-over". Arm 102 is carried by a standard 104 suitably secured to pipe 58, a spring 105 serving to keep damper 103 on until the note is played, when the choke coil 17' not only performs its function of increasing the tone and holding down the arc, but also undamps vibrating member 60 and permits it to sound. When its corresponding key is released, coil 17' as quickly 65 becomes de-energized and permits pressure of damper 103 against the vibrating member 60, thus cutting the tone off sharply, and with no 70 disagreeable "hold-over". The wires 16' and 75

12' from the coil 17', Fig. 18, connect respectively with wires 16 and 12 of Fig. 1.

It will be noted that the legs of vibrating member 60 are turned so as to project along the pipe for purposes of economy of space and protection 80 against being hit.

I have found the choking action of coil 17' with its iron core necessary if increased loudness of speech is to be attained without in any sensible way altering the pulsating circuit per se, or increasing its arc, and that this is increasingly true in degree as the lower end of the scale is approached. As the frequencies of interruption increase, the iron core becomes less necessary, and as the masses moved are also smaller, the attack is sufficiently quick and self-damping becomes sufficient. Thus it will commonly not be necessary to carry the choking action of the resistance which permits a steady current, throughout the entire scale, though there may be cases where it will be desirable so to do. 90

In Fig. 19 another means of damping the tones of the low bass octaves of the instrument is shown. A portion of a resonator 58^a has associated with it a magnet 106 which acts as a relay, 100 and serves to close a circuit which may be always of constant pressure, said circuit operating to close the aperture 108 in resonator 58^a, said aperture being preferably placed at a point not a natural partial of the tone intended and given 105 by the full pipe. The magnet 109 in circuit with magnet 106 performs the arduous work of the real damping. 110, 111 indicate connections from magnet 106 to the wires 16 and 12 of Fig. 1 or similar wires. said magnet being here employed instead of the resistances 17 of Fig. 1. These dampers will probably be required for only the lower and larger pipes, and will probably be used on the lowest two octaves and possibly only on the very lowest octave. In some cases it might not be necessary to employ any damping, but where the maximum clearness of speech is required, it is preferable to damp the lower notes 115 in the finer types of instrument.

Aperture 108 is normally open, rocker arm 112 carrying the pad or damper 114 being raised through the agency of spring 113, but is closed by said damper while the tone is being produced, the rocker arm lifting the pad or damper the instant the key is released. When the damper is removed and the aperture uncovered, the pipe no longer suits the pitch of reed 60, and the resonance and consequently the tone, immediately cease. The magnet 109 is in circuit with a source of power 115 which is constant or not altered when the instrument is played. 116, 117 indicate co-acting contacts carried respectively by rocker arm 118 and by the non-conducting fiber head 106^a of magnet 106, the wire 119 from magnet 109 being connected to a stud or pin 119^a 120 passing through said head 106^a. These pins or studs are of conducting material, the current passing from one pin to the other through the arm 118. 125

It is to be understood, therefore, that for the 140 lower octaves of the instrument, one or more, it is preferred to use the separate coil and core 17' illustrated in Fig. 18, while for most or all of the other octaves of the instrument it is preferred to use the double-coil magnets illustrated 135 in Fig. 2.

Musical instruments of the type here disclosed are usually actuated by a uni-directional current of about thirty volts, which in the case of the present invention renders it necessary to use rela- 150

tively low resistance for any coils intended to produce a suitably strong, steady magnetization of cores for the purposes herein set forth and explained. When, therefore, in the specification 5 or claims the expression "strong" or "relatively strong" is used, it is to be understood as meaning a very appreciable part of the total possible magnetization of a core for, as has been pointed out herein, it is desirable to have the steady magnetization strong, and the tone may be increased with each increment of such strength up to, but not passing, that degree of saturation which will still enable the fluctuant current to make itself sharply felt with each increment of its current.

15 I claim:—

1. The herein described method of increasing the action of a unidirectional pulsated current traversing a coil around a core of magnetizable metal, which consists in causing an armature associated with said core to act in a relatively strong magnetic field which, of itself and apart from the field produced by the fluctuant current, is sensibly steady during the action of said unidirectional pulsated current, both said currents 25 being of the same polarity.

2. The herein described method of rhythmically vibrating a sounder of a musical instrument, which consists in rhythmically pulsating a unidirectional current; passing said current 30 about a core to which a portion of said sounder acts as an armature; and causing said core to be rendered strongly magnetic apart from, and with the same polarity as that produced by said pulsated current, the increase in the magnetism 35 produced by said unpulsated current being steady during the action of said unpulsated current.

3. The herein described method of rhythmically vibrating a sounder of a musical instrument, which consists in providing a unidirectional rhythmically pulsated electrical current 40 rendered operative at will; operating said sounder by said rhythmically pulsated electrical current; and creating a strong magnetic field during the action of said pulsated current, thereby 45 greatly increasing the effect of said last-named current, both said currents being of the same polarity.

4. The herein described method of rhythmically electromagnetically vibrating a sounder by 50 a rhythmically pulsated, unidirectional current, which consists in delivering said current at will to an electromagnet operating said sounder; and creating and maintaining throughout the entire action of the pulsated current a strong magnetic field which, of itself and apart from the field produced by the fluctuant current is sensibly steady, and upon which steady field the fluctuant field is superposed, thereby greatly enhancing the effect 55 of the fluctuant current, both said currents being of the same polarity.

5. The herein described method of electromagnetically producing rhythmically timed movements in a sounder, serving in part as an armature to an actuating magnet, said method consisting 60 in supplying the actuating magnet, during the operation of said sounder, with two kinds of magnetization of like polarity, one strong and sensibly continuous and the other pulsatory in accordance with the rhythmical movement desired.

6. The herein described method of producing and augmenting the timed, rhythmical movements of a sounder of a musical instrument, which 70 consists in rhythmically varying the strength of a relatively strong unpulsating magnetic field by

superposing upon said field rhythmically pulsatory increments of like polarity and of the periodicity predetermined.

7. An electromagnetically operated musical instrument, comprising a series of sounders each 80 adapted to produce a selected partial to be used as a component of the desired tone; a source of current; pulsation-producing means in circuit with said source; a magnet associated with each of said sounders; connections between said pulsation-producing means and said magnets for passing a unidirectional pulsated current through the coils of said magnets of a periodicity determined by the associated pulsation-producing means; means for simultaneously passing a continuous 85 unpulsated current through said magnets during the speaking of their associated sounders; relays in circuit with said magnets; means for passing both the pulsated and unpulsated currents through said relays; means in circuit with said 90 relays for selecting and mixing the partials to be sounded as the desired composite tone; and expression-control means in circuit with said partial-mixing system.

8. In an electromagnetically operated musical 100 instrument, a series of sounders each adapted to produce a selected partial to be used as a component of the desired tone; a magnet associated with each of said sounders; a source of current; means for passing a pulsatory current through 105 said magnets; and means for simultaneously passing an unpulsated current through said magnets, said means including a resistance in circuit with each of said magnets and a condenser in shunt with each of said resistances.

9. In an electromagnetically operated musical instrument, a source of current; a series of sounders each adapted to produce a selected partial to be used as a component of the desired tone; magnets associated with said sounders; means for 115 passing a pulsatory current through the coils of said magnets; and means for simultaneously passing an unpulsated current through the coils of said magnets, said means including a resistance in circuit with each of said magnets and condensers placed respectively across the break and across the coil of each of said magnets.

10. In an electromagnetically operated musical instrument, a source of current; a series of sounders each adapted to produce a selected partial to 125 be used as a component of the desired tone; magnets associated with said sounders, each of said magnets carrying two coils; means for passing a pulsatory current through one coil of said magnets; means for simultaneously passing an unpulsated current through the other of said coils; and condensers across the poles of one coil of said magnets.

11. In an electromagnetically operated musical instrument, a source of current; a series of sounders each adapted to produce a selected partial to be used as a component of the desired tone; magnets associated with said sounders, each of said magnets provided with a permanently magnetized core; means for passing a pulsatory current 135 through the coils of said magnets; and means for maintaining the magnetism of the cores of said magnets.

12. In an electromagnetically operated musical instrument employing magnets for operating the 145 sounders of said instrument; means for maintaining the magnetism of the cores of said magnets, comprising a switch, magnets in circuit with said switch, contacts in circuit with said magnets, and means for opening and closing said contacts; a 150

- source of current; pulsation-producing means in circuit with said source; and means for supplying current to said first-mentioned magnets without passing said current through said pulsation-producing means. 5
13. In an electromagnetically operated musical instrument, speaking units each comprising a vibrating body; a support for the vibrating bodies, said support forming part of the magnetic circuit; a resonator associated with each vibrating body; and magnets carried by said support, the core of each magnet projecting into close proximity to each vibrating body, the air-gap between the cores of said magnets and the vibrating bodies being very slight and the magnetic circuits short. 10
14. In an electromagnetically operated musical instrument, a speaking unit comprising a vibrating body; a resonator associated with said body; a movable member supported by said vibrating body; a magnet core associated with said vibrating body, the air gap between said core and the vibrating body being slight; a choke coil carried by said resonator; a damper controlled by said coil; and means for opening and closing the circuit of said coil. 15
15. In an electrically operated musical instrument, a speaking unit comprising a vibrating body; a resonator associated with said vibrating body; a movable member in proximity to said vibrating body; a magnet associated with said body, the air-gap between the core of said magnet and the vibrating body being slight; and means for damping the tones produced by said speaking unit, comprising a relay magnet, a second magnet in circuit with said relay magnet, a source of current in circuit with said second magnet, a damper controlled by said magnets, and means for opening and closing the circuits of said magnets. 20
16. In an electromagnetically operated musical instrument, a source of current; a series of sounders each adapted to produce a selected partial to be used as a component of the desired tone; magnets associated with said sounders; and means for simultaneously passing a unidirectional and a pulsated current through said magnets. 25
